(57) **CLAIM**

The ornamental design for the supporting wire base for floral arrangements, as shown and described.

DESCRIPTION

FIG. 1 is a perspective view of the supporting wire base for floral arrangements of this invention;

FIG. 2 is an end view thereof;

FIG. 3 is an opposite end view thereof;

FIG. 4 is a top view thereof;

FIG. 5 is a bottom view thereof;

FIG. 6 is a right side view thereof;

FIG. 7 is a left side view thereof; and,

FIG. 8 is another perspective view thereof, wherein the broken lines showing various flowers and greenery represent environment and form no part of the claimed design.

1 Claim, 4 Drawing Sheets---
